SANDAL

Nina Baroumes, Juneau, Territory of Alaska

Application February 20, 1953, Serial No. 23,716

Term of patent 3½ years

(Cl. D7—7)

To all whom it may concern:

Be it known, that I, Nina Baroumes, a citizen of the United States, residing at Juneau, in the Territory of Alaska, have invented a new, original, and ornamental Design for a Sandal, of which the following is a specification, reference being had to the accompanying drawing, forming a part hereof.

I claim:

The ornamental design for a sandal, as shown.
NINA BAROUMES.
